UNITED STATES PATENT OFFICE.

T. F. RUMBOLD, OF ST. LOUIS, MISSOURI.

IMPROVEMENT IN ROLLING-MILLS.

Specification forming part of Letters Patent No. 39,960, dated September 15, 1863; antedated June 2, 1863.

To all whom it may concern:

Be it known that I, T. F. RUMBOLD, of the city and county of St. Louis, in the State of Missouri, have invented a new and useful Machine for Rolling Metal in a Regular or Irregular Form; and I do hereby declare that the following is a full, clear, and exact description of the construction and the operation of the same, reference being had to the accompanying drawings, constituting a part of this specification, in which—

Figure 1, Sheet 1, is a side or front view of the machine, adapted for rolling tapering bars or beams without a curve being imparted to them. Fig. 2 is a top view, and Fig. 3 a transverse section, of the same. Fig. 4 is a modification of Fig. 1 plan. Fig. 5 is a modification of the plans Figs. 1 and 4. Figs. 6 and 7 show two of the forms of iron that may be produced by the spiral mold-rollers.

Similar letters of reference in the several figures indicate corresponding or similar parts.

The invention which I have developed consists in making rollers whose molds, instead of passing around like common rollers in a ring-like form, pass around in a spiral or screw-like form, thereby allowing the opportunity of gradually decreasing or increasing the depth or width of said groove or mold to a much greater length than on common rollers.

To enable others skilled in the art to make and use my invention, I will proceed to describe the same with reference to the drawings.

A B represents two rollers, constructed according to my invention, for rolling and tapering bars or beams, as shown in Fig. 6 (said figure being one of the many shapes that can be formed on this same principle, and will be used throughout this specification merely because it is convenient to illustrate the principle.) The rollers are fitted one above another in a rolling-mill frame or housing, C C, in any of the well-known ways, and are geared together, as at D D, so as to run at equal speeds. The circumference of the rollers have spiral or screw-like molds formed on them by cutting spiral grooves into the metal. On one roller this groove or mold turns from right to left and on the other from left to right. The flanges of the upper or larger roller, which form a guard or guide as the iron is being

rolled, match the grooves that are between the molds or working-surface of the lower or smaller roller, and are so arranged that when the two rollers are geared together they (the flanges of the larger roller) extend into the grooves of the smaller roller to a greater or less extent, accordingly as the case may require; but in this respect the spiral-mold rollers do not differ from the common rollers that are found in rolling-mills. It is evident that the mold thus formed is continuous from one end of the rollers to the other end, and as the flanges *a b* are right and left handed and their depth gradually increased on one in one direction and gradually decreased on the other in a reverse direction, the rollers, when in motion, present a continually-changing working-surface, *c d*, giving the impress of the mold to the metal as it passes between them, thus imparting the tapered form to the beam or bar of iron.

In Fig. 2 I have illustrated by red lines the gradual changes made in a bar with all its sides parallel during the stage of its progress through the rolls. The bar, after being once introduced between the rolls, does not have to be removed and again inserted through another part of the same rollers, but being once introduced it follows laterally the screw-line of the mold, and at the same time feeds longitudinally through the rollers, as illustrated in red. Although, as stated, it does not have to be introduced a second time into the same rollers, yet the iron bar or beam will have to be inserted between different rollers, having different-sized molds on them, until it is brought to the proper form; but in this respect, also, the number of times the iron has to be passed between the rollers does not differ from the common mode of rolling metal.

The great idea of my invention is this: The molds are made to pass around my rollers in this screw-like form, giving a much longer changing working-surface than in the common rollers, whose molds only pass around once, allowing alterations only to the extent of the circumference of the same, whereas in the spiral molds modifications as to the depth or width can be made at any point of the whole length of said spiral mold, which pass several times around the rollers. The bars, when they are completed by the plans 1, 2, and 3, are

without a curved bend in them. They, however, may require to be trued, unless fed through the rollers under a tension, as practiced in the rolling of polished shafting.

I have described the mold as being formed by cutting spiral grooves into the metal of the rollers; but it is obvious that they might be formed by constructing the spiral flanges separate from the rollers, and afterward applying them firmly on rollers of proper gradually-rising outline. It also is obvious that the shape or configuration of the flanges, molds, and rollers may be altered so as to produce any of the known forms of beams or bars, as has been previously stated, without departing from the principle involved in the spiral-mold rollers.

In Fig. 4 the molds are represented as being much wider than the flanges or spaces between them. With this formation broader bars or pieces of iron can be rolled than in the plan previously described. The width and depth of the mold may be varied at will by increasing the pitch of the same and adding to its depth.

By examining Fig. 4 it will be seen that the working-faces *c d* are parallel with the axis of the rollers, notwithstanding the fact that these faces united form a conic roller, or, in other words, are formed on a conical foundation. This parallelism is necessary in order to roll the bars without a curve being imparted to them.

In Fig. 5 I have shown working-faces *c d* of the molds running at an angle to the axis of the rollers A B. This change does not affect the result of the rollers, so far as reducing and tapering or otherwise shaping the iron goes,

but it does produce a very essential effect upon the form of the iron. It, by reason of the conical shape of each section of the working-face of the mold, due to the angle given thereto, gradually bends the bar into the form illustrated by Fig. 7. The extent and character of the bend imparted to the iron is just in proportion to the degree of angle or inclination that the working-surface of the rollers differ from the center line or axis of the rollers, which degree of angle may be altered at pleasure and used along only a portion of the length of the rollers, in connection with the working-surface on the other portions, which are parallel with the axis of the rollers, or it may be on the whole length of the rollers, as represented. Now, with my invention, if it is desired to roll tapered iron, or other metal of any form, whether square, flat, round, T-shaped, swelled, regular, irregular, &c., either with or without a curved bend in it, it can be done by the employment of the spiral-mold rollers, the mold of said rollers being made the shape and size of the iron or other metal that is to be rolled.

What I claim as my invention, and desire to secure by Letters Patent, is—

The forming of the mold or working-surface around the rollers in a spiral or screw-like form, making one continuous track from one end of the rollers to the other end of the same, so as to be the counterpart of the bar or beam that is desired to be rolled, substantially as set forth.

T. F. RUMBOLD.
